UNITED STATES PATENT OFFICE

CHESTER A. JOHNSON, OF CHICAGO, ILLINOIS, ASSIGNOR TO JEFFERSON ELECTRIC COMPANY, OF CHICAGO, ILLINOIS, A CORPORATION OF ILLINOIS

BOX MOUNTING

Application filed June 21, 1926. Serial No. 117,277.

This invention relates generally to switch boxes or outlet boxes and particularly to mounting means for such boxes comprising spaced parallel bars for locating the box at a point removed from a support such as a stud.

During the construction of buildings and prior to the application of lath and plaster, switch boxes or outlet boxes are placed between studs or joists from which it is desired that they be supported. In my copending application Serial No. 62,949, filed October 17, 1925, I have shown a box mounted slidably on two parallel bars secured across spaced studs. The box disclosed has slotted projections through which the bars extend to provide a retaining engagement and a slidable relation. This construction necessitates threading of the bars into the slots before both ends of any bar can be mounted. A channel bar is disclosed, and the arrangement further is such that, when mounted, the bar is twisted and its sides in part clamped together in such a manner that either the clamping, or twisting, or both, serve to bind the bar on the edges of the slot, thereby to prevent sliding. The present invention preserves substantially all the advantages of the prior construction, and provides in addition certain other advantages which will hereinafter be more apparent.

One object of the present invention is to provide the box with receiving members for the supporting bars which members are open at the ends to engage a bar by movement laterally toward the bar.

Another object is to provide bar-engaging members which encompass the spaced bars whereby to hold them from separation after the box has been mounted.

Still another object is to provide bar-engaging means projecting from the box and so formed that they are rigid and sturdy in construction and free from a liability to injury on accidental dropping or other mistreatment of the box.

Various other objects and advantages of the invention will be apparent from the following description of the exemplary embodiment

of the invention shown in the accompanying drawings.

In the drawings the invention is illustrated as applied to a switch box mounted in a wall composed of studs to which wooden lathing and plaster are applied; therefore, lath-supporting means are also illustrated as a part of the device.

In the drawings,

Figure 1 represents a switch box mounted between studs on a wooden lath wall.

Fig. 2 is an enlarged full sized view of a switch box taken on the line 2-2 of Fig. 1.

Fig. 3 is a cross section of the box taken on the line 3-3 of Fig. 2.

Fig. 4 is a view of the bars and bar-engaging means taken on the line 4-4 of Fig. 1.

Fig. 5 is a detail fragmentary view showing the manner of hanging the box on a bar in the process of mounting.

Although the drawings and the description, hereinafter following, are detailed with reference to the preferred embodiment of the invention, it is to be understood that this is not to be considered as a limitation of the invention to the form shown. The invention is capable of a variety of modifications and alternative constructions, such as may fall within the scope of the appended claims.

The preferred embodiment of the invention as shown in the drawings comprises, in general, the combination of a switch box 10, parallel supporting bars 11 and 12, and bar-engaging means carried by the box and generally designated 13. The wall in which the box is mounted comprises in the present instance spaced studs 14 and 15 and wooden laths 16, some of which are intercepted by the box in mounted position, thus presenting free projecting lath-ends 17. The box when mounted is used also for supporting the free ends 17 of the intercepted lathing. For this purpose there is employed on each side of the box a channel member 18 formed preferably of sheet metal. The lath channels 18 are suitably secured to the sides of the box as by spot welds 20. Each lath channel comprises a bottom portion 21, a front side 22, and a rear side 23, all three parts extending beyond the

end of the box to form the bar-engaging means 13.

The supporting bars are preferably also channel shaped and are mounted with the openings 24 thereof directed away from each other for a purpose which will be more apparent hereinafter. Each lath-channel bottom 21 is recessed as at 25 from its end to receive a bar 11 or 12 and the recess 25 is shaped to conform within certain limitations to the shape of the bar. Thus the bar and box may be engaged by relative motion of the box laterally of the bar, the bar entering the receiving recess 25.

When the bars 11 and 12 are mounted in the wall and also entered into the four receiving recesses herein provided in the lath channels, the box is firmly held between the bars against removal therefrom.

In the present instance it will be noted that the bars 11 and 12 have rounded bottoms 26 and that the recess 25 is so formed that the bar may turn in the recess. This is due particularly to the abrupt termination of the rear side 23 of each lath channel, whereby the edge of recess 25 does not contact the corresponding side of a bar 11 or 12. However, means is provided otherwise to prevent turning of the bar in the recess and yet to obtain all the advantages of an open ended receiving recess for the bars. One particular reason for mounting the channel bars with the channel bases toward each other is to provide two spaced horizontal parallel members about which the box may be clinched. The front sides 27 of the channel bars 11 and 12 provide such members in the form of strips over the edges of which engage clinching means on the box.

In the present instance the front side 22 of the lath channel is extended and bent over to form a hook 28 projecting over and into the recess 25. Opposing hooks 28 may thus clinch the bars 11 and 12, there being two on each end of the box as shown in the drawing. In addition, each hook 28, cooperating with the edge of the recess 25, provides the means to prevent turning of the bars in the recesses. The short rear lath-channel side 23 permits the channel bar to be associated with the lath-channel members by a sort of rolling-in motion when entering the recess 25. This is indicated by the fragmentary view in Fig. 5. Such rolling-in action is pivotal about the outer edge of the front bar face 27 and the bottom of the groove under the hook 28.

The bar receiving means, such as the recess 25 and the hook 28, is so disposed that the channel bars 11 and 12 are angularly directed, that is, each bar in the present instance has a flat side 29 inclined to the vertical plane. This flat side is indicated as the rear face 29 of the bar. The bar is adapted to be secured as by nails 30 to one of the studs 14 or 15. It is therefore provided with

spaced nail holes 31 which, in the present instance, pass through both sides 27 and 29 of the bar. Each end of the bar is thus adapted to be nailed to a stud, and as illustrated, both ends are thus secured although this is not necessary. When properly mounted in the wall each bar has its flat side 29 lying in a vertical plane; but, because each bar is angularly disposed at the box, each bar becomes twisted on mounting, the bar 11, Fig. 2, tending to turn clockwise at the box. As it is held by the hook 28 and the recess 25, turning of the bar clockwise is impossible. The bar thus bears against the edge of the recess. Said recess 25, being formed in sheet metal stock, presents a very sharp edge which receives considerable force from the torsion in the bar and thus holds the box against sliding readily along the parallel bars.

In mounting a box on a side wall the most practical procedure is first to mount the top bar 11 with the U opening upwardly. When a nail 30 is used, it is unnecessary to insert it so deeply into the stud 14 that both sides are squeezed flatly together. However, this can be done to any extent desired or permitted by the bar without interfering with the desirable relations of the parts. The bar material may be made sufficiently rigid so that squeezing of the sides together is unnecessary, and preferably it is thus so rigid in order to resist the torsion produced. Such a mounting of the bar will cause the same to be disposed with both sides 27 and 29 in a vertical plane. The box is then associated with the bar by relatively entering the bar into the recess 25, this being done in the present instance by a rolling-in action to engage under the hook 28. This done the bar hangs by the hook 28 and projects forwardly and at an angle from the wall as suggested by the fragmentary view in Fig. 5. This is accomplished quickly and without difficulty. The means for mounting the other end of the box is now brought into action. As the box has preferably a duplicate end structure the relation of the bar to box is substantially like that described for mounting the first bar, but the mounting steps are different. The lower bar 12 is associated with the box by a similar rolling-in action. Pressure on the lower end of the box to move it into the vertical plane of the wall necessarily twists the upper bar 11 thus binding the box against a sliding motion. The lower bar is then nailed into place, and as it is fixedly secured against the stud it becomes twisted in a manner similar to the upper bar, the twisting binding the box to hold it against sliding. This construction securely holds the box and the bars together, the bars being encompassed by the clinching hooks 28 which are provided on the ends of the box whereby to prevent separation of a bar and the box, endwise of the box and laterally of the bar.

I claim as my invention:

1. A box mounting comprising, in combination, a box, a pair of bars of irregular cross section adapted to be mounted in spaced parallel relation in a wall, projecting hooked means on the ends of the box adapted to engage and partially to encompass said two bars, and means adapted to engage each bar to compel twisting the bar between a mounted end and the box.

2. A box mounting having, in combination, a box, lath receiving channel strips secured to the side of the box and extending beyond the ends thereof, said extending ends each having the base of the channel recessed from the end angularly with respect to the sides of the lath channel and having the front side of the channel bent over toward said recess to form a hook, two mounting bars adapted to be received in said recesses and to be engaged by said hooks to prevent relative rotation in one direction therebetween, and means for attaching said bars at a point removed from the box in parallel relation in a wall, said means engaging said bars at an angle to the engagement of said bars with said box to tend to rotate said bars in the direction resisted by the hooks on said box.

3. A box mounting comprising, in combination, a box, a pair of flat sided bars adapted to be mounted in spaced parallel relation in a wall, means projecting outwardly from each end of the box, each of said means being recessed at the end to receive a bar and having means thereon adapted to engage said bar to prevent relative rotation thereon in one direction, said recesses being angular with respect to the front face of the box to compel said bar to twist in the resisted direction when said box is mounted in the wall.

4. A box mounting comprising, in combination, a pair of bars adapted to be mounted in a wall in spaced parallel relation, a box having members secured thereto and extending beyond opposite sides of said box, said members being recessed at an angle to the front of the box to receive said bars therein, means engaging said bars to prevent rotation in one direction relatively to said box, and means spaced from said box for mounting said bars in the wall, said means being adapted in mounting to tend to rotate said bars against the engaging means on said box.

5. A box mounting comprising, in combination, a box, a pair of bars adapted to be mounted in a wall in spaced parallel relation, and means on said box adapted to engage each of said bars in non-rotative relation in one direction and at an angle to the plane of the wall, each of said bars when mounted in the wall being adapted to maintain said box substantially parallel to the plane of the wall against the torsional force

produced in the other bar by moving the box into the plane of the wall.

6. A box mounting comprising, in combination, a bar adapted to be mounted in a wall, a box, means on said box engaging said bar at an angle to the plane of the wall, said engagement being such as to prevent relative rotation therebetween in one direction, and means engaging said box to draw said box in the resisted direction substantially into the plane of said wall.

7. A box mounting comprising, in combination, a bar having a longitudinal opening therein adapted to be mounted in a wall, a box, means on said box engaging the opening in said bar at an angle to the plane of the wall, and means for holding said box in the plane of the wall against the resisting torsional force of said bar after said box has been moved from the engaging to the mounting position.

8. A box mounting comprising, in combination, a bar adapted to be mounted in a wall, a box, means providing an engagement between said box and said bar, said engagement being at an angle to the plane of the wall, and means engaging said box to maintain said box substantially in the plane of said wall against the torsional force of said bar created when said box is moved from its bar engaging position to its normal mounted position.

9. A box mounting comprising, in combination, a box, a pair of bars adapted to be mounted in spaced parallel relation in a wall, means on said box adapted to engage said bars to prevent relative rotation therebetween in one direction, and means for twisting said box against said bars in the resisted direction to maintain said box in mounted position.

10. A box mounting comprising, in combination, a box, a pair of bars adapted to be mounted in a wall in parallel relation, means on said box adapted to engage one of said bars at an angle to the plane of said bars, and means on said box adapted to engage the other of said bars to hold said box substantially parallel to the plane of said bars whereby the first mentioned bar will be twisted to maintain the box in mounted position.

11. A box mounting comprising, in combination, a box, a pair of bars adapted to be mounted in a wall in spaced parallel relation, and means providing an interlocking engagement between said bars and box arranged to clamp said box to the bars when the bars and box are in their normal mounted position, said engagement being releasable only when said box is out of its normal mounted position.

12. A box mounting comprising, in combination, a box, a pair of bars of irregular cross section adapted to be mounted in a wall in spaced parallel relation, and means on said box providing an interlocking engage-

ment with said bars, said engagement being possible only at an angle to the normal position of the box in the wall to induce a torsional force in the bars when the box is in its normal position.

5 13. A box mounting comprising, in combination, a bar adapted to be mounted in a wall, a box, means on said box capable of freely engaging or releasing said bar only when said box is at an angle to the plane of the wall, and means for mounting the box in parallelism with the plane of the wall.

10 14. A box mounting comprising, in combination, a bar adapted to be mounted in a wall, a box, means on said box engaging or releasing said bar only when said box is at an angle to the plane of the wall, and means for holding said box in the plane of said wall after said box has been moved into such a plane against the resisting torsional force of said bar.

15 15. The method of securing a switch box in an adjustably fixed position between two studs which comprises mounting a bar between two studs, associating the box slidably but non-rotatably with said bar with the face of said box at an angle to the plane of the wall, moving the box against the torsional force of the bar to bring the face of the box into the plane of the wall and bind the box against sliding movement on the bar, and securing the box in this position.

20 16. The method of securing a switch box in an adjustably fixed position which includes the steps of effecting a non-rotatable engagement between the box and a stationary wall part so that the front face of the box is at an angle to the plane of the wall, moving the front face of the box substantially into the plane of the wall against the resisting force of said non-rotatable engagement, and securing the box in the last mentioned position.

25 In testimony whereof, I have hereunto affixed my signature.
